UNITED STATES PATENT OFFICE

156,694

AMPHIBIAN AIRCRAFT

Alfred Z. Boyajian, Farmingdale, N. Y., John Gitz, North Wales, Pa., and Percival H. Spencer, Fort Lauderdale, Fla., assignors to Republic Aviation Corporation, Farmingdale, N. Y., a corporation of Delaware

Application October 24, 1946, Serial No. 134,217

Term of patent 14 years

(Cl. D71—1)

To all whom it may concern:

Be it known that Alfred Z. Boyajian, John Gitz, and Percival H. Spencer, citizens of the United States and residents respectively of Farmingdale, in the county of Nassau and State of New York; North Wales, in the county of Montgomery and State of Pennsylvania; and Fort Lauderdale, in the county of Broward and State of Florida, have jointly invented a new, original, and ornamental Design for an Amphibian Aircraft, described and claimed in the following specification and shown in the accompanying drawings, wherein:

Fig. 1 is a plan view of an airplane embodying the present design with the landing gear protracted;

Fig. 2 is a front elevation thereof with the landing gear retracted;

Fig. 3 is a side elevation thereof with the landing gear retracted;

Fig. 4 is a perspective view of the airplane from the front with the landing gear protracted; and

Fig. 5 is a similar view from the rear.

We claim:

The ornamental design for an amphibian aircraft, substantially as shown.

ALFRED Z. BOYAJIAN.

JOHN GITZ.

PERCIVAL H. SPENCER.
